METHOD FOR ATTACHING METAL RINGS
TO PAPER BOTTLESWilliam Pelzer, Yonkers, and Harold H. Pelzer,
New York, N. Y.

Application December 1, 1941, Serial No. 421,200

6 Claims. (Cl. 153—1)

This invention relates to paper bottles and containers of the type shown in Letters Patent of the United States No. 2,267,993, granted to us December 30, 1941, and the method of attaching the metal rings, U-shaped in cross-section, for securing the parts of the bottle or container, and more particularly the invention relates to the mode of attaching the metal neck rings to paper bottles in which the paper body is folded or plaited to form the bottle neck and mouth.

Heretofore in attaching metal rings to paper bottles or containers for securing the parts together it was customary to secure the ring in place by spinning the edge of the ring into the paper, or by means of radially moving squeezing or expanding dies. These methods are not satisfactory for all purposes and cannot satisfactorily be employed on bottles or containers having folded or plaited parts which the rings engage owing to the different thicknesses against which the ring is spun, squeezed or otherwise clinched. It will be apparent that where the paper of the bottle or container is folded or plaited the thickness at one section will be single ply and at the folded or plaited sections the thickness will be three-ply, and that therefore a metal ring cannot be uniformly applied by spinning or radial squeezing to clinch the ring in place at all sections without cutting into the paper at the folds or plaits or leaving gaps under the ring between folds or plaits.

The object of our invention is to provide a method of applying a U-ring to the paper body of a bottle or container by relative axial movement of a pair of die members, within which the ring is held, to cause contraction of the edge of the outer flange of the ring, as distinguished from contraction or turning in by spinning, or contraction by radially moving squeezing rings or jaws.

In carrying our invention into effect we force the outer edge of the U-ring into a die member having an inward contraction, preferably curved, whereby the edge of the ring is circumferentially contracted while the paper body upon which the ring is to be secured moves in the same direction with and at the same speed as the ring, and whereby when the turned edge of the ring touches the paper the contraction continues while the ring edge is extruded axially of the die member substantially concentric with the tubular paper body forming a circumferential shoulder on the ring, whereupon extrusion ceases and the final movement of the male die member causes compression of the outer flange of the ring, the pressure being applied at the shoulder formed by the

extrusion and the saddle of the U-ring, causing it to spread and clinching the paper between the shoulder and the edge of the inner flange.

The method is illustrated in the accompanying drawings, in which—

Figure 1 is a central vertical section on the line 1—1 of Figure 2 of a form of die mechanism whereby the improved method of contracting and clinching of a U-ring may be effected.

Figure 2 a horizontal cross-section on the line 2—2 of Figure 1.

Figures 3, 4, 5 and 6 are fragmentary vertical sections of the mechanism shown in Figure 1 illustrating successive stages in the contraction and clinching of the U-ring upon the neck of a paper bottle.

Figure 7 an elevation and part sectional view on an exaggerated scale illustrating the clinched ring on a smooth surfaced body.

Figure 8 an elevation of part of a bottle body or neck having a plaited surface and showing the flow of the ring edge down and between the plaits, and

Figure 9 a cross section on the line 9—9 of Figure 8.

Referring to the drawings, and more particularly to Figures 1 and 2, which illustrate a form of tool that may be employed for practicing the method of our invention, 1 indicates a cylindrical body within which slides a sleeve 2 having an inner bevelled edge 3, which engages the correspondingly bevelled edge of four radially set jaws 4. Sleeve 2 is shown as having two arms 5 in which a rod 6 is journaled and on which lever 7 is sleeved as seen in Figure 1. This lever is suitably fulcrumed for imparting reciprocating movement to sleeve 2 for closing and holding the jaws 4 in the closed position after a ring has been inserted.

The jaws 4 constitute the female member of the die for contracting and clinching the bottle or container ring. These jaws are normally held open to receive a ring and slide against the underside of flange 8 of the body 1 to set the jaws in the closed operative position after a ring is inserted. For this purpose the jaws are provided with a groove on the upper face in which is seated a coiled spring or pair of spring rings 9 which tend to move and hold the jaws in the open

position shown more clearly in Figure 2 to permit insertion of a ring. The undersides of the jaws are machined to present when closed a short cylindrical surface 10 and an inwardly curving surface 11, Figure 1. The upper sides of the jaws are bevelled to present when closed a conical en-

trance 12 for the paper tube upon which a metal ring is to be contracted and clinched. Between the under and upper surfaces 11—12 the jaws are machined to present when closed a short cylindrical surface 13. The flange 8 of the body 1 is bevelled as shown at 14 to correspond with the bevelled surface 12 of the jaws to present an extended conical surface entrance for the paper tube.

Adapted to slide within the jaw-closing sleeve 2 is a cylindrical anvil 15 having a circular seating groove 16 for the U-ring 17, shown in Figures 3 to 5 before the contracting operation, and in Figure 6 at the finish of the contracting and clinching operation. In Figure 7 the ring 17 and paper tube 18 are shown in exaggerated dimensions to more clearly show the cross-sectional configuration imparted to the ring and the bend to the paper tube at the finish of the contracting and clinching operation.

Referring now more particularly to Figures 3 to 6 it will be seen that the saddle 19 of ring 17 has a smaller radius than the seating groove 16 of anvil 15 which results in a circumferential spacing between the inner flange of ring 17 and the cylindrical anvil wall 21 and which part of the anvil wall is circumferentially machined to form a seat for the laterally projecting flange 22 of the U-ring. The anvil 15 projects above the seat for the ring flange 22 and is tapered to form a conical guide 23 for the U-ring as it is dropped into position, and this tapered extension forms an anvil for the paper tube guide 24 which has an internal taper to provide a close fit on the anvil part 23 while permitting the rim of the guide 24 to seat upon ring flange 22 to hold the ring firmly upon the anvil seat as seen in Figures 5 and 6.

The anvil 15 is provided with a pair of lugs 25, Figure 1, between which a lever 26 is hinged by pin 27, and this lever is suitably fulcrumed to impart reciprocating movement to the anvil after the sleeve 2 has been moved and held in position for locking the jaws 4 in operative position. The tube guide 24 is illustrated as secured to the end of a rod 28 which may be supported and moved in any suitable manner.

The operation for applying a ring to a paper tube is as follows, reference being had to Figures 3 to 6: The jaws 4 being in the open position of Figure 3 a ring 17 is dropped upon the anvil with ring flange 22 resting on the anvil seat and the outer curve of ring saddle 19 in contact with the outer periphery of ring groove 16. Sleeve 2 is then moved upward to close jaws 4 to the position shown in Figure 4. At this stage and step of the method, the upper end of the outer flange of the U-ring, which flange is deeper than the inner flange, fits closely within the cylindrical section 10 of the closed jaws 4, and the ring is thus set to receive the end of paper tube 18. As the paper tube is inserted into the die, the guide 24 follows or moves with it to assist in causing the tube to enter and seat itself squarely within the full depth of the U-ring, and at the same time the guide 24 is seated upon the ring flange 22 to hold the ring firmly upon the anvil to prevent its displacement as seen in Figure 5. The metal ring and paper tube are now in position for the ring contraction and clinching. The anvil 15 is now forced upward by means of lever 26 thereby forcing the U-ring upward within the die and causing its outer flange to contract and curve inward as it engages the curved surface 11 of the jaws 4, and this upward movement of the anvil carries the tube 18 and guide 24 upward along with the U-

ring and at exactly the same rate of movement. This movement maintains the tube seated in the ring saddle; holds the ring seated in groove 16; and maintains guide 24 in position relative to the anvil extension 23 and paper tube 18 so that the paper tube above the ring flange 22 will have a solid backing or anvil to receive the pressure from the exterior when the ring is being clinched. This movement of the tube, ring and solid backing causes the edge of the ring when it touches the paper tube to bend over the edge of cylindrical surface 13 of the jaws 4 and extrude from the jaws concentric with the paper tube and in contact therewith. This contacting of the extruded edge of the ring prevents further contraction of the ring by the curved surface 11 and therefore the further inward movement of the anvil effects a compression of the ring between the surface 11 and ring groove 16. This step forms the shoulder and sharp angle 29 on the outer flange of the ring, see Figure 7, which clinches the metal ring upon the paper tube by compressing the paper circumferentially at a downward angle upon the shoulder 30 of the inner flange of the metal ring. If now the inward pressure of anvil 15 is continued to the limit of its movement, as seen in Figure 6, the pressure applied on the shoulder of the outside flange of the metal ring will cause the ring saddle 19 to slide inward in the anvil groove 16, and since the ring flange 22 is firmly held to its seat on the anvil, the inside flange of the metal ring, which has no resisting wall due to the clearance between it and cylindrical wall 21 of the ring groove 16, will bend inward forming a circumferential bead 20 which serves to stiffen the ring and provide a retaining bead for the ordinary sealing disk which seats against the ring flange 22. To remove the paper tube with its clinched ring from the tool the levers 7 and 26 are operated to retract sleeve 2 and anvil 15, respectively, which allows the jaws 4 to open and frees the clinched ring from the anvil 15 to permit extraction of the tube with its ring from the tool and retraction of the guide 24. The anvil 15 is then in the position shown in Figure 3 prepared to receive another ring whereupon the jaws are closed and the operation repeated.

In attaching and clinching a ring upon a smooth surfaced paper tube as shown in Figure 7, the extruded part 31 of the ring is formed into a short cylindrical section of reduced diameter. When attaching and clinching a ring upon a tube having folded or plaited sections to form the neck of a bottle, as shown in Figures 8 and 9, the extruded parts 32 form short bands which overlap the folds or plaits 33, and the sections 34 of the ring flow inward off the curved surface 11 of the die jaws between the folds or plaits until contact is made with the paper tube sections 35, whereupon the ring sections 34 curve parallel with the tube sections 35 a very slight extent governed by the depth of the outer flange of the ring and the thickness of the paper at the folds or plaits. This flow of the metal of sections 34 of the ring between the folds or plaits produces an inward curve at the intersection of ring sections 32 and 34 as seen in Figure 9, and when the final vertical squeeze is imparted to the ring as in Figure 6, the ring sections 32 and 34 are pressed firmly against the respective paper tube sections 33 and 35, and continued pressure produces the bead 20 as above described.

What we claim is:

1. The method of contracting and clinching upon a paper tube a metal U-shaped ring hav-

ing its outer flange deeper than the inner flange and a rounded shoulder on the inner flange, which consists in seating the ring on a male die member, inserting the paper tube into the U-ring, forcing the outer flange of the ring axially into a female die member having an inward curve to contract the flange, simultaneously moving the paper tube with and in the same direction as the ring, continuing the axial movement of the ring and tube until the contracted end of the ring flange extrudes from the die member, and then compressing the outer ring flange in the axial direction between the die members to form a shoulder thereon and compress the paper at a downward angle between said shoulder and the shoulder of the inner flange.

2. The method of contracting and clinching a U-shaped metal ring upon a paper tube having folded or plaited longitudinal sections forming a bottle neck, which consists in seating the ring on a male die member, inserting the paper tube into the U-ring, forcing the outer flange of the ring axially into a female die member having an inward curve to contract the flange, simultaneously moving the paper tube with and in the same direction as the ring, continuing the axial movement of the ring and tube until the contracted end of the ring flange extrudes from the die member, then compressing the contracted outer ring flange in the axial direction between the die members to form angular bends at the extruded parts of the ring adjacent the folded or plaited sections of the tube, and further compressing the outer ring flange to force said angularly bent extruded sections and the ring sections between the folded or plaited tube sections upon the paper tube to clinch the ring thereon.

3. The method of contracting and clinching a U-shaped metal ring having its outer flange deeper than the inner flange and a rounded shoulder on the inner flange upon a paper tube having folded or plaited longitudinal sections forming a bottle neck, which consists in seating the ring on a male die member, inserting the paper tube into the U-ring, forcing the outer flange of the ring axially into a female die member having an inward curve to contract the flange, simultaneously moving the paper tube with and in the same direction as the ring, continuing the axial movement of the ring and tube until the contracted end of the ring flange extrudes from the die member, then compressing the outer ring flange in the axial direction between the die members to form angular bends at the extruded parts of the ring adjacent the folded or plaited sections of the tube, and further compressing the outer ring flange to force said angularly bent extruded sections and the ring sections between the folded or plaited tube sections upon the paper tube at a downward angle to compress the paper between said outer flange sections and the shoulder of the inner flange to clinch the ring thereon.

4. The method of contracting and clinching upon a paper tube a metal U-shaped ring having a laterally projecting flange for seating a closure member, which consists in seating the ring on a male die member, inserting the paper tube into the U-ring, forcing the outer flange of the ring axially into a female die member having an inward curve to contract the flange, simultaneously moving the paper tube with and

in the same direction as the ring, continuing the axial movement of the ring and tube until the contracted end of the ring flange extrudes from the die member, then compressing the contracted outer ring flange in the axial direction between the die members to produce an angular bend in the extruded part for clinching the ring upon the paper tube, and further compressing the ring to cause the inner ring flange between its lateral flange and saddle to bulge inward to form a circumferential bead for retaining a bottle sealing member.

5. The method of contracting and clinching a U-shaped metal ring, the outer flange of which is deeper than the inner flange and having a lateral closure seating flange forming a shoulder on the inner flange, upon a paper tube having folded or plaited longitudinal sections forming a bottle neck, which consists in seating the ring on a male die member, inserting the paper tube into the U-ring, forcing the outer flange of the ring axially into a female die member having an inward curve to contract the flange, simultaneously moving the paper tube with and in the same direction as the ring, continuing the axial movement of the ring and tube until the contracted end of the ring flange extrudes from the die member, then compressing the outer ring flange in the axial direction between the die members to form shoulders at the extruded parts of the ring adjacent the folded or plaited sections of the tube, and further compressing the outer ring flange to force said shouldered extruded sections and the ring sections between the folded or plaited tube sections upon the paper tube at a downward angle to compress the paper between said outer flange sections and the shoulder of the inner flange to clinch the ring thereon.

40 6. The method of contracting and clinching a U-shaped metal ring, the outer flange of which is deeper than the inner flange and having a lateral closure seating flange forming a shoulder on the inner flange, upon a paper tube having folded or plaited longitudinal sections forming a bottle neck, which consists in seating the ring on a male die member, inserting the paper tube into the U-ring, forcing the outer flange of the ring axially into a female die member having an inward curve to contract the flange, simultaneously moving the paper tube with and in the same direction as the ring, continuing the axial movement of the ring and tube until the contracted end of the ring flange extrudes from the die member, then compressing the outer ring flange in the axial direction between the die members to form shoulders at the extruded parts of the ring adjacent the folded or plaited sections of the tube, further compressing the outer ring flange to force said shouldered extruded sections and the ring sections between the folded or plaited tube sections upon the paper tube at a downward angle to compress the paper between said outer flange sections and the shoulder of the inner flange to clinch the ring thereon, and further compressing the ring to cause the inner ring flange between its lateral flange and saddle to bulge inward to form a circumferential bead for retaining a bottle sealing member on the seating flange.
